(Cl. D49—6)

To all whom it may concern:

Be it known that I, Leland H. Snyder, a citizen of the United States and a resident of the city of Chicago, in the county of Cook and State of Illinois, have invented a new, original, and ornamental Design for an Electric Iron or Similar Article, of which the following is a specification, reference being had to the accompanying drawing, forming a part thereof.

On the drawing:

Figure 1 is a top plan view of the electric iron, or similar article, showing my new design;

Figure 2 is a side elevational view;

Figure 3 is a front elevational view; and

Figure 4 is a rear elevational view thereof.

I claim:

The ornamental design for an electric iron or similar article, as shown.

LELAND H. SNYDER.
